UNITED STATES PATENT OFFICE.

DWIGHT B. LEE, OF DETROIT, MICHIGAN.

DESIGN FOR A COMBINED AUTOMOBILE BODY AND HOOD.

Application filed January 21, 1929. Serial No. 29,686. Term of patent 14 years.

To all whom it may concern:

Be it known that I, DWIGHT B. LEE, a citizen of the United States, residing at Detroit, county of Wayne, State of Michigan, have invented a certain new, original, and ornamental design for Combined Automobile Body and Hood, of which the following is a specification, reference being made to the accompanying drawing, forming part thereof.

Figure 1 is a side elevation of an automobile body, showing my new design.

Figure 2 is a perspective view of the body shown in Figure 1.

Figure 3 is a detail section, as indicated by the arrows and line III, Figure 1.

A characteristic feature of my design is that a molding strip upon the vertical side of the ridge on the cowl and hood extends in a straight line effect beneath the short windows to the rear of the body.

I claim:—

The ornamental design for a combined automobile body and hood, as shown and described.

In testimony whereof I sign this specification.

DWIGHT B. LEE.
